CLAIM

The ornamental design for a fluid collection apparatus, as shown and described.

DESCRIPTION

FIG. 1 is a perspective view of a fluid collection apparatus configured in accordance with the present invention; FIG. 2 is a top view of the article of FIG. 1; FIG. 3 is a bottom view of the article of FIG. 1; FIG. 4 is a left side view of the article of FIG. 1; FIG. 5 is a right side view of the article of FIG. 1; FIG. 6 is a front view of the article of FIG. 1; and, FIG. 7 is a back view of the article of FIG. 1.

The broken lines in the drawings are included for the purpose of illustrating portions of the fluid collection apparatus that form no part of the claimed design. The fluid collection apparatus is shown with a symbolic break in its length. Any portions not shown between the break lines form no part of the claimed design.
